UNITED STATES PATENT OFFICE.

JOHN FREDERICK SCHLAPPI, OF SIOUX CITY, IOWA.

EMULSIFYING-MACHINE.

1,353,425.

Specification of Letters Patent. Patented Sept. 21, 1920.

Application filed April 2, 1920. Serial No. 370,833.

To all whom it may concern:

Be it known that I, JOHN FREDERICK SCHLAPPI, a citizen of the United States, and a resident of Sioux City, in the county 5 of Woodbury and State of Iowa, have invented certain new and useful Improvements in Emulsifying-Machines, of which the following is a specification.

My invention is an improvement in emulsifying machines, and has for its object to provide a machine of the character specified by means of which an emulsion between two or more substances not capable of chemical combination may be intimately 15 mixed to form the emulsion.

In the drawings:

Figure 1 is a vertical section of the emulsifying machine,

Fig. 2 is a top plan view.

In the present embodiment of the invention, a cup shaped casing is provided, consisting of a body portion 1 and an integral end 2, the other end of the casing being closed by a head 3 which has a flange 4 fitting about the end of the body. This casing is mounted on a shaft or spindle 5, which may be connected with any suitable means for rotating said spindle at a high rate of speed, and the closed end 2 of the casing has 30 an opening through which a threaded portion 6 on the spindle is passed.

The spindle has an annular rib 7 between the threaded portion and the body of the spindle, which rib abuts the outer face of 35 the bottom 2, and a sleeve 8 is threaded onto the threaded portion of the spindle. This threaded portion of the spindle has oppositely arranged notches 9 which form ports for placing the sleeve 8 in communication 40 with the interior of the cup shaped casing, that is, with the annular space between the body of the casing and the sleeve.

Referring to Fig. 1, it will be seen that these ports extend longitudinally of the 45 spindle and then radially, and the sleeve has openings at the outer ends of the ports. The sleeve is threaded onto the threaded end of the spindle, as before mentioned, and it passes through an opening in the head 3 at 50 the opposite end from the spindle. Outside the head a nut 9 is threaded onto the sleeve

for holding the head in place. The body 1 of the casing has an annular rib 10 just above the ports 9, the said rib being of considerable depth, as shown, and above the rib 55 and between the rib and the head there is provided a series of longitudinally extending slots or passages 11. At the forward side of each slot there is arranged a blade or vane 12 extending radially of the casing, 60 the said blades or vanes being spaced a slight distance from the slots or passages, as shown more particularly in Fig. 1.

In operation, the materials to be emulsified are fed through the sleeve 8, being conveyed to the outer end thereof in any suitable or desired manner. These materials pass through the sleeve and by way of the ports 9 into that portion of the casing 1—2 between the rib 10 and the closed end 2. 65

The centrifugal force tends to hold the materials against the peripheral wall of the casing, and such materials are compelled to travel inwardly over the rib 10 as they move toward the ports 11. The materials are 75 thoroughly mixed and emulsified during their passage from the sleeve to the ports 11 into any suitable container which is arranged outside of the casing, it being understood that the casing is rotatable, within 80 the container which is fixed. The vanes 12 prevent the liquid from circling with the casing 1—2 during its operation. The emulsifier is simple in construction, easily operated and inexpensive. 85

I claim:

1. A device of the character specified, comprising a closed casing, means for rotating the casing, said casing having discharge ports near its outer end, a feed tube 90 at the axis of the casing, said tube having discharge ports at its inner end and at the inner end of the casing, and the casing having an internal annular rib between the discharge ports of the casing and the discharge 95 ports of the feed tube for constraining the material to move inwardly toward the center of the casing before passing through the discharge ports, the casing having radial tongues adjacent to the discharge ports, and said feed tube being imperforate between the annular rib and the outer end of the cas- 100

ing to constrain all the material to feed at the inner side of the rib.

2. A device of the character specified, comprising a closed casing and means for rotating the case, said casing having at its bottom an inlet and near its top a series of outlets and means adjacent to the outlet for deflecting the material outward through

the outlet, said casing having an internal circumferentially extending annular rib between the inlet and the outlets, and means for feeding the material at the bottom of the casing and between the rib and the said bottom. 10

JOHN FREDERICK SCHLAPPI.
